JOHN K. SEYMOUR INVENTOR.

BY *Rickey Slough & Tales*

His ATTORNEY'S

UNITED STATES PATENT OFFICE.

JOHN K. SEYMOUR, OF ELYRIA, OHIO.

GAME AND TOY.

Application filed January 9, 1922. Serial No. 527,835.

To all whom it may concern:

Be it known that I, JOHN K. SEYMOUR, a citizen of the United States, residing at Elyria, in the county of Lorain and State of Ohio, have invented certain new and useful Improvements in Games and Toys, of which the following is a full, clear, and concise description as will enable others skilled in the art to which this invention appertains to make and use the same.

This invention relates to games and toys, and particularly to such games and toys involving the element of chance rather than that of skill, and in which a large number of different combinations resulting from the manipulation of the device by the player may result.

A particular object of my invention is to provide a game or toy apparatus which, when manipulated by the player, will give one or another of a large number of different resulting indications which may be to the consequent variable advantage or disadvantage of the particular player.

Another object of my invention is to provide such an apparatus which will be of attractive appearance, and at the same time will be durable and cheap in construction.

Other objects of my invention and the invention itself will be better understood by reference to the description of several specific embodiments thereof, and in which description reference will be had to the drawings illustrating such embodiments. In the drawings:

Fig. 1 shows a top plan view of an embodiment of my invention.

Fig. 2 shows a vertical sectional view on the line 2—2 of Fig. 1 except that the rotary element is shown in elevation.

Fig. 3 shows a view similar to Fig. 1 of a different embodiment of my invention.

Fig. 4 shows a vertical sectional view on the line 4—4 of Fig. 3.

Fig. 5 shows a game scoring annular disc in connection.

Referring now to the embodiment illustrated in Figs. 1 and 2 at 2 I show a metallic frame having circular walls 3 and a dished top wall 4, the dished top wall having a central opening 5 into which opening the rotatable wheel 6 is supported on a pivot pin 7. The pivot pin 7 is carried in a circular wooden disc or block 9, the disc 9 being secured by nails 8 to the side walls 3 of the metallic frame.

The pin 7 has a point 10, upon which point the rotatable wheel 6 is pivoted, there being a recess 11 extending axially of the wheel, the said pin fitting loosely in the recess and the recess having a curved end wall.

The wheel 6 has a corrugated edge 12, the diameter of the wheel being slightly less than the diameter of the central opening 5 of the downwardly dished frame top wall 4 so that when rotated by a handle 13, the wheel, due to its inertia mass, will continue to spin for a considerable time without its periphery engaging the edges of the opening 5. The downwardly dished annular wall 4 thus provided is divided into a number of spaces, preferably as illustrated, equal, these spaces being determined by struck-up dividing portions of the wall 4 shown at 14.

I also provide a small ball 15 such as a steel marble, the ball being placed in the portion 4 of the frame 2 will, by gravity, descend until it occupies some such position as illustrated where it contacts and fits within one of the peripheral notches or indentations 16 of the wheel 12.

When in such a normal position, the apparatus is operated by suddenly spinning the wheel by manipulating the handle 13, and the ball 15 is caused, by the notches 16 successively engaging it, to be flung upwardly and forwardly in the direction of rotation of the wheel, and in the annular portion 4 of the frame 2, bouncing upwardly and forwardly thereon until the wheel 6 comes to rest, whereupon the ball 15 will come to rest between some two adjacent divisions 14 and in contact with a particularly lettered, grooved or indentation such as one lettered, "All" or 10 or 1, 2, 3, 4, or 5 as the case may be, and depending upon the chance position the ball assumes at the end of the spinning of the wheel.

In playing a game by means of the marks shown on the apparatus of Fig. 1, one can move one or more so-called "men" along a circular track having divisions, to the right or to the left from a starting point according to the indication secured by the apparatus as above described; or the apparatus may be used to predetermine the progress of a contestant in many different kinds of games.

Referring now to the embodiment of my invention illustrated in Figs. 3 and 4, in this apparatus I do not provide the wheel 61 with peripheral notches such as the notches 16 of

Fig. 1, but instead provide the wheel with pins 161, the wheel proper 61 being disposed so that the level of its top surface will coincide substantially with the level of the edge 5 of the downwardly dished top wall 41. In this embodiment also, I may construct the apparatus, as illustrated, of wood, the frame member 21 and the wheel member 61 being preferably so constructed. This wheel like 10 the wheel of the first embodiment will have handles 13 for the purpose of spinning the wheel, and the pins 161 will project from its top surface 50 in a circle adjacent the edges of the wheel, the spaces between the pins 15 being suitably designated as illustrated, or 15 as otherwise required to suit the particular game played; and the spaces on the annular downwardly dished portion 41 of the frame 21 are provided by pins 141 projecting from 20 the top surface near the central opening of the portion 4 so that these pins perform the same function as the raised portions 14 in the embodiment of Fig. 1, that is, of making the ball 15 come to rest definitely in the one or 25 the other division of the dished portion 4 or 41, the openings of the two embodiment structures being substantially the same.

Fig. 5 shows a game scoring annular card or disc adapted to be placed over the game 30 apparatus illustrated in the other figures and which comprises a circular pathway having divisions marked thereon, such divisions comprising a plurality of start divisions 51, 52, 53, and 54, and other intervening divisions 55 over which so-called "men" as in the game of parchesi, may be moved from one start position to a final home position which may be one of the start 35 points. In using this game, the player would move the men to the right or to the left depending upon the indication given by the game apparatus placed in the center of the annular disc. This game may be played variously depending upon the rules which 40 are arbitrary and may be varied.

Having thus described my invention, I wish it to be understood that numerous and 45 extensive departures may be made from the embodiments herein illustrated and described but without departing from the spirit of my invention, and that the divisions of the two operative elements may be made considerably different from that herein illustrated and differently designated, 55 but remaining within the purview of my invention. What I claim is:

1. In a game apparatus, the combination with a centrally disposed rotatable wheel, a spinning handle whereby which the wheel 60 may be rotated, a frame having side walls and a top wall, the top wall having a downwardly dished portion with a centrally disposed opening, means to pivot the said wheel with its periphery adjacent the edges 65 of the said opening, a ball adapted to be

placed in the said dished frame top and normally adapted to rest against the edge of the wheel, said edge having a plurality of projections extending therefrom, said ball adapted to rest between two of the said 70 projections and to be flung upwardly and forwardly by the wheel when rotating, said downwardly dished frame portion having spaced projections adjacent the edge of its central opening to cause the ball to come 75 to rest after being agitated by the rotated wheel to a definite position between two of the said wheel projections and to one side or the other of the said dished portion 80 projections.

2. In a game apparatus, a frame, a top wall therefor having an annular downwardly dished portion, means to pivot said wheel within the central opening of the said portion and with its periphery adjacent the 85 edges thereof, the wheel periphery having a plurality of closely adjacent projections, and the said annular portion having a plurality of projections less in number than the said wheel projections and adjacent the 90 edge of the said opening, and a ball adapted to be agitated by the rotation of the wheel within the opening and to come to rest between two of the last named projections and against an adjacent pair of the first named 95 projections.

3. In a game apparatus, the combination with a frame, a dished top therefor, an opening in the center of the said top, a rotatable wheel disposed within the said opening, the said wheel having a portion of its periphery disposed above the level of the said opening, said peripheral portion having a plurality of closely adjacent projections, said dished top being divided by radially disposed divisions into a plurality of spaces, and a ball adapted to be placed in the said dished top and adapted to rest against the wheel peripheral serrated portion and to be agitated thereby when the wheel is rotated, said spaces being marked 100 differently and characteristically, said wheel surfaces being also differently marked whereby the ball coming to rest within one of the said spaces and against one of the 105 said serrations may give an indication of value in play to the player rotating the wheel, a circular track, said track being divided into a plurality of divisions adapted to mark the progress of markers placed on the said divisions, said indications provided by the positioning of the ball, the wheel and the space in which the ball comes to rest determining the movement of the said 110 markers over the said divisions.

4. In a game apparatus, a combination with a frame, a dished top therefor, a central opening within the said dished top, a rotatable wheel disposed within the said opening and rotatable out of contact with 115 the said opening, a ball adapted to be 120

the said top, said top being divided into a plurality of spaces bordering around the said opening, a plurality of projections extending above the surface of the wheel and closely spaced together, a ball adapted to be placed in the said dished top and against the said projections, the diameter of the ball being greater than the distance sep-

arating the projections, and means to prevent the ball from coming to rest on the dividing line between the dished top spaces.

In witness whereof I have hereunto signed my name this 6th day of January, 1922.

JOHN K. SEYMOUR.
